ULTRASONIC TEST PROBE

Michel A. F. Sirovica, Doylestown, and Julius F. Tibolla,
Yardley, Pa., assignors to Curtiss-Wright Corporation,
a corporation of Delaware

Application April 3, 1959, Serial No. 55,341

Term of patent 14 years

(Cl. D52—1)

Figure 1 is a perspective view of an ultrasonic test probe showing our new design.

Figure 2 is an enlarged fragmentary view of a portion of the face of the ultrasonic test probe.

The undisclosed side of the ultrasonic test probe is substantially the same in appearance as the side shown. The shroud on the barrel of the handle portion is hollowed out and open at the rear, and the rear of the test probe is substantially plain in appearance.

We claim:

The ornamental design for an ultrasonic test probe, as shown and described.
